UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A MISS'S POLONAISE.

SPECIFICATION forming part of Design No. 14,804, dated February 19, 1884.

Application filed November 19, 1883. Term of patent 3½ years.

To all whom it may concern:

Be it known that I, LOUISE TULLY, of the city, county, and State of New York, have invented and produced a new and original Design for a Pattern of a Miss's Polonaise, numbered 8,978; and I do hereby declare that the engraved prints accompanying this specification convey to any one accustomed to using paper patterns a clear understanding of how a garment made up by the pattern will appear.

The design shows close-fitting basque-fronts buttoned all the way down, with a deep oval drapery that exhibits draping plaits in its back edges, concealing their lower edges, and a

close-fitting back falling in a deep oval drapery, and displaying under-folded plaits at the lower ends of its side back seams, coat-sleeves and a standing collar being added.

What I claim as my invention, and desire to secure by Letters Patent, is—

The design for a miss's polonaise, as shown in the engraved prints accompanying this specification.
